UNITED STATES PATENT OFFICE.

KENNETH RUSHTON, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

ASH PAN HANGER FOR LOCOMOTIVES.

Application filed December 28, 1920. Serial No. 433,577.

To all whom it may concern:

Be it known that I, KENNETH RUSHTON, a citizen of the United States, residing in Philadelphia, Pennsylvania, have invented 55 certain Improvements in Ash Pan Hangers for Locomotives, of which the following is a specification.

One object of my invention is to provide a means for securing the ashpan of a locomotive to the mud ring of the boiler so that the joint will accommodate itself to the shape of the pan, and a further object of the invention is to provide means whereby the pan can be readily detached from the 15 boiler structure.

In the accompanying drawings

Fig. 1 is a longitudinal sectional view through the rear end of a locomotive showing the fire box and the ashpan and my improved means of connecting the ashpan to the boiler structure.

Fig. 2 is a transverse sectional view on the line 2—2, Fig. 1.

Figs. 3 and 4 are perspective views illustrating details of the invention.

1 is the frame of the locomotive, 2 is the boiler, in the rear end of which is the fire box 3. The fire box casing is separated from the casing of the boiler by a mud 30 ring 4. This mud ring extends entirely round the bottom of the fire box, and within this fire box is a grate of usual construction which is not shown in the present instance.

35 6 is the ashpan which is located directly under the fire box so as to receive and hold the ashes passing through the grate. This ashpan may be of any shape desired, depending upon the type of locomotive to 40 which it is applied. In the present instance the rear axle 7 on which the wheels 8 are mounted passes through a recess 9 formed in the under side of the ashpan. The pan has inclined sides which direct the ashes 45 towards openings 10 which are normally closed by sliding doors 11. In the present instance the doors are actuated by a lever 12 pivoted at 13 to the frame of the locomotive and connected to the sliding doors 50 by a link 14 and the two sliding doors are connected together by a bar 15. The flanges 5 of the ashpan 6 are at an angle to the

body of the pan, and this angle varies slightly in each locomotive, and in order to accommodate this angle so that there will be no difficulty in coupling the ashpan to the mud ring of the boiler structure I secure a series of angle plates 16 to the flanges 5 of the ashpan, and these angle plates are arranged in pairs with the upright portions facing each other and spaced apart sufficiently to allow the tongue 17 of a bracket 18 to extend into the space between the two angle plates as shown in Fig. 1. The brackets 18 are secured by bolts or 65 other fastenings to the mud ring 4 of the boiler structure, and a bolt 19 extends through openings in the angle plates and in the tongue 17 securing the parts together and firmly holding the ashpan to the boiler 70 structure. By making this connection in the form of a hinge the couplings will accommodate themselves to the angles of the ashpan flange, and when it is desired to remove the ashpan all that is necessary to be 75 done is to withdraw the bolts 19. As shown by the dotted lines in Fig. 3 the tongue 17 of the bracket 18 may be made of considerable length and cut off when the parts are to be assembled, as in some instances the 80 space between the boiler structure and the ashpan may vary in different locomotives.

I claim:

1. The combination in a locomotive, of a boiler structure having a fire box; an ash pan located under the fire box; a series of brackets depending from each side of the fire box; plates secured to each side of the ash pan; and fastening devices arranged longitudinally of the pan and extending 90 through the brackets and plates.

2. The combination in a locomotive, of a boiler structure having a fire box; an ash pan under the fire box, said ash pan having an angular flange at each side; angle plates 95 secured to the upper surfaces of the flanges; brackets secured to the boiler structure at each side of the fire box, said brackets having tongues extending between the angle plates of the ash pan; and bolts arranged 100 longitudinally of the pan and coupling the plates to the brackets.

KENNETH RUSHTON.
